SKID RAIL STRUCTURE FOR FORGE
FURNACES

John D. Nesbitt, Sylvania, Ohio, assignor to Surface Combustion Corporation, Toledo, Ohio, a corporation of Ohio

Application November 20, 1950, Serial No. 196,582

1 Claim. (Cl. 263—6)

This invention relates to a fuel heated forge furnace for use in plants where work pieces are shaped between forging dies, as in hammer, press or roll forging. The general object is to provide improvements in skid rail structures for a fast heating furnace which will heat work pieces uniformly to forging temperature within the shortest possible time, thus with a minimum scale. This application is a continuation in part of application Serial No. 35,922 filed June 29, 1948, and now abandoned, and is directed more particularly to means for preventing local overheating of the work and means for supporting the work in the furnace. For a consideration of what I consider to be novel and my invention, attention is directed to the following portion of the specification and the drawings and concluding claim thereof.

In the accompanying drawings, forming part of this specification,

Fig. 1 is a longitudinal vertical section of a furnace embodying the present invention.

Fig. 2 is a transverse sectional view of the improved furnace.

Fig. 3 is a transverse sectional view of the work supporting means in the furnace chamber.

Fig. 4 shows how exposed ends of the work piece may be protected from overheating.

Fig. 5 shows how the support and guide rails of Fig. 4 may be maintained in alignment.

Fig. 6 shows a modification of the support means of Fig. 5.

Fig. 7 shows a water piping layout for the work support means of Figs. 2 and 3.

Fig. 8 shows a water piping layout for the work support means of Fig. 5.

Fig. 9 shows a water piping layout for the work support means of Fig. 6.

The furnace comprises a refractory lined tunnel forming a cylindrical chamber 10 which will ordinarily be supported on horizontally disposed rails 13 atop supporting pillars 14, the tunnel having lateral arms 12 which rest on said rails. The tunnel is anchored at one end to the supporting frame of which the pillars 14 form a part, the balance of the tunnel being free to move on said rails as its length increases due to thermal expansion.

The work pieces to be heated are passed through the furnace chamber at a level which is substantially within the central portion of the heating chamber. The means for supporting the work at such level comprises internally cooled supports generally indicated at 15, the water supply pipe being indicated at 45 and the water

outlet pipe at 46. The charging end of the furnace is at the left as viewed in Fig. 1 and the work pieces are fed into the furnace by a reciprocating pusher head 16 in front of which the work pieces are placed by hand or otherwise. The heated work pieces exit from the furnace on a downwardly inclined support 17. The flue gases exit from the furnace through front and rear vertical flues 18 and 19.

10 The inner lining 20 of the tunnel 10 is comprised of fused bubble alumina which is a high temperature refractory having heat insulating properties. A layer of heat insulating material 21 will ordinarily be interposed between said lining and the steel casing 22 of the tunnel 10. Full aerated fuel, preferably gaseous, is employed to heat the exposed surface of said lining to elevated temperature, the lining having a plurality of tangential fuel inlet ports 23 for this purpose so that the fuel will wash said surface and burn in contact therewith.

20 The means for delivering the aerated fuel under pressure to the inlet ports 23 comprises for each port a refractory nozzle 25 which projects a short distance into said port. A supply pipe 27 delivers the aerated fuel under pressure to a holder 26 for the refractory nozzle 25.

25 The several fuel supply pipes 27 for the several burners or fuel discharge nozzles 25 are connected in sets to individual fuel supply manifolds 37, thereby permitting ready control of the heat input to the furnace at longitudinal intervals or zones by control of valves 40 individual to supply pipes 41 which deliver to said manifolds.

30 The work supporting means, or skid rails 15 are supported at longitudinal intervals atop transversely extending walls 36 which also serve to prevent draft through the lower portion of the furnace and additionally serve to divide the lower portion of the heating chamber into longitudinal zones which are useful for heat control purposes.

35 Where work pieces are adapted to be pushed through the furnace in end to end relation, as the square section pieces W in Figs. 2 and 3, the supporting means 15 therefor comprises a pair of laterally spaced internally cooled rails 42 which together form a cradle wherein the work pieces W are supported. These rails are interconnected at longitudinal intervals by tubular connecting members 43 so that cooling water in the rails 42 will also maintain the tubular connecting members 43 relatively cool. Where the members 43 are short and tubular it is not necessary to provide for a positive directional flow of

cooling water therethrough. It is sufficient to provide continuous flow through each of the rails 42 whereby any steam formed in the members 43 will rise to the cool stream in the rails 42, 43 will rise to the cool stream in the rails 42, 43 will rise to the cool stream in the rails 42, condense, and cool water will then run downward into the members 43. In practice, the thermal gradients in the members 43 have provided a natural circulation sufficient to avoid steam formation, due in part to the short members 43 required. When positive unidirectional flow through the members 43 is not provided it is preferred to recirculate water through the rails in a closed system to prevent accumulations of deposits such as lime in the rails and members. Where the problem of cooling the members 43 becomes greater than suitable orifices may be installed in the lines as shown in Fig. 7, where valves 50 and 51 are installed outside the furnace heating chamber 10 for water flow control, one valve 50 at a rail inlet to the furnace and the other valve 51 at the paired rail outlet from the furnace. This provides by flow restrictions a positive continuous directional flow from the unrestricted rail inlet 52 through the members 43 to the unrestricted rail outlet 53, as shown by directional arrows adjacent members 43.

It will be appreciated that where square sectional pieces W are pushed end to end along pairs of rails as shown in Figs. 2 and 3 there is a continuous pressure on the rails to spread them. The connecting members 43 effectively maintain alignment of pairs of rails without additional water cooled tubes being supplied to the furnace.

In a furnace having a circular combustion chamber which is tangentially fired as illustrated in Fig. 2 it is possible to maintain combustion against the refractory wall of the furnace as a relatively thin sleeve in the chamber and maintain unusually high wall temperatures for rapid "high heat head" heating. The central part of the chamber within the dashed line circle 54 is filled with products of combustion finding their way towards the end flues. These products of combustion are relatively inactive gases as compared to the reacting gases in the gas flame of the outer "sleeve," hence the scale formation is held to a minimum during the fast heating of the work. The temperatures maintained in the heating chamber, generally in excess of 2600° F., are so high as to practically preclude the use of other than water cooled work supports, and the method of firing demands that the water cooled supports be kept out of the sleeve of burning gases in the furnace chamber, otherwise they would chill the gases before combustion was complete, and would absorb heat by convection as well as radiation removing as much as 40% more heat from the furnace. In a furnace having an inside chamber diameter of about 20 inches the sleeve of burning gases may be considered as about 4" thick, and if the rails are kept 4" or more from the refractory walls they do not seriously affect the heating efficiency of the furnace. When the furnace has an inside chamber diameter of about 40 inches, the burning gas sleeve has a thickness of about 6 inches.

Where the work pieces are required to be pushed through the furnace broadside first (as the work pieces WP in Figs. 4, 5 and 6), the ends of said pieces tend to become overheated. This is due to a radiation phenomenon where the furnace wall temperature is considerably in excess

of the final desired work temperature. To prevent this overheating the pathway 15 along which the work pieces move through the furnace comprises, in addition to the internally cooled work supporting skid rails 47 (Figs. 4, 5 and 6), a pair of internally cooled side rails 48 which form a channel between which the work pieces are moved. Each side rail 48 is located with respect to the moving work so as to shield it from the excessive end heating effect of the entire side of the furnace wall, hence the end of the work piece is said to move in the "shadow" of the side rail. For this reason the side rails 48 are called shadow rails.

In rapid heating furnaces of this type billets may be heated to forging temperature with not over 0.002 inch of scale whereas conventional forge furnaces would allow to form at least .010 inch of scale, usually more. The improved forging die life possible with the materially reduced scale has been remarkable, usually of the order of 2 to 4 times the life formerly obtained. Where the "shadow rails" are not used the non-uniform heating of the ends overheats the steel and at the same time melts the thin scale thereon, making a sticky scale which rapidly deteriorates the forging dies. It has been demonstrated that to take full advantage of the rapid heating possible where a high heat head furnace is used, if billets are pushed broadside through the furnace, it is necessary to prevent overheating of the billet ends. The disclosed "shadow rails" serve this purpose admirably well.

In any refractory lined furnace for heating work to forging temperature there is a distinct advantage in using shadow rails when heating work with a high heat head in a manner tending to heat one portion of the work faster than another. When operating with a heat head (the difference between furnace temperature and final desired work temperature) of 100° to 400° F. or more, especially where the furnace temperature is over the scale melting temperature of 2440° F., if the work heats at the ends or at light sections faster than at other portions, then the faster heating portions may easily reach 2440° F. at their surface and form a plastic scale before the remainder of the piece reaches forging temperature. This plastic scale is worked into the surface of the piece in the dies and is very detrimental to the dies, causing materially shortened die life and subsequent machining troubles. Where shadow rails and support rails are both used, each side pair of shadow and support rails may be interconnected with water cooled tubular sections 55 as shown in Fig. 5, and the flow therethrough may be controlled by valves 56 and 57 as shown in Fig. 8. The support rails may also be joined by similar tubular sections 58 making the support rails and the shadow rails into a single structure as shown in Fig. 6. The controlled directional flow may be maintained quite easily by restricting flow in alternate rails at the inlet ends thereof, and at the outlet ends of intermediate rails as illustrated by valves 56 and 57 in Fig. 9.

It is believed to be apparent from the foregoing that the present invention provides for improvements in skid rail structure for a fast heating furnace which is well adapted for its intended purpose.

Having thus described my invention, I claim:

Skid rail structure for supporting work pieces 75 in a furnace comprising a plurality of substan-

tially parallel internally cooled skid rails for conveying work pieces end to end through the furnace, cross pieces interconnecting said rails at longitudinal intervals to keep them from spreading, said cross pieces being tubular and so connected that cooling fluid flowing through the rails may also flow through the cross pieces, means forming a flow restricting orifice in one rail at the inlet end thereof and means forming a flow restricting orifice in an adjacent rail at the outlet end thereof whereby cooling fluid entering the unrestricted end of one skid rail is diverted in part through each cross piece and thence flows through the unrestricted outlet of the adjacent skid rail.
